Primary Examiner — Jennifer Rivard(74) Attorney, Agent, or Firm — Duane Morris LLP(57) CLAIM

The ornamental design for a hair styling device holster, as shown and described.

DESCRIPTION

FIG. 1 is a perspective view of the hair styling device holster; FIG. 2 is a front view of the hair styling device holster; FIG. 3 is a rear view of the hair styling device holster; FIG. 4 is a top side view of the hair styling device holster; FIG. 5 is a bottom side view of the hair styling device holster that is opposite the view in FIG. 5; FIG. 6 is a side view of the hair styling device holster; and, FIG. 7 is a side view of the hair styling device holster. The broken line showing of structure is for illustrative purposes only, and forms no part of the claimed design.
